United States Patent Office

Des. 216,018
Patented Nov. 18, 1969

216,018

PUBLIC ADDRESS SYSTEM

G. Jerome Sieler, 1037 N. La Brea,
Los Angeles, Calif. 90038

Filed Nov. 27, 1968, Ser. No. 14,689

Term of patent 14 years

Int. Cl. D14—03

U.S. Cl. D26—14

FIG. 1

FIG. 2.

FIG. 3.

FIG. 4.

FIG. 1 is a front perspective view of a public address system, showing my new design;

FIG. 2 is a side elevation as seen from the right of FIG. 1;

FIG. 3 is a rear elevation thereof of FIG. 1; and

FIG. 4 is a bottom plan view thereof.

I claim:

The ornamental design for a public address system, substantially as shown.
